SHEARER

Richard V. Hirsch, South Gate, Calif.

Application November 22, 1944, Serial No. 564,612

9 Claims. (Cl. 30—43)

1

This invention concerns shearing and cutting devices and any other kind of device in which the principles and novelty of this disclosure are likely to be useful. The preferred form of the invention, however, is for an electrically operable razor and the like.

The razor herein disclosed operates on the hidden shearing principle wherein the shearing edges are perpendicular to the surface to be shorn or at a slight angle thereto. The shearing elements consist of a plurality of compact blades having their gliding or skin contact edges in a single plane, the skin contact edges of the blades being flat and void of all sharp edges or points, thus avoiding any risk of cutting the face or other surface over which the blades may be employed. All the blades are superimposed in side by side relationship and such a unit of blades may be described as a laminated cutting unit which presents to the surface of the skin a smooth non-cutting edge. Every blade of the razor is perpendicular to the center line of the driving shaft or driving lever. Every blade acts as a cutter and does not have any combing action which might be imagined from the general battlement construction of the razor blades. Although flat blades are preferred, it is also intended to include curved blades nested together as it is evident that the invention would successfully work with variously shaped blades that are not flat. When the device of this invention is properly employed and run along the surface of the skin, some hairs are pressed or bent over toward the skin when they are cut, but most of the hairs will be cut while normal to the skin in that these hairs would pass through the cutout portions of the blades; some hairs would be pushed to the right or left of the approaching blade front and thus enter the cutout portions at a slight angle.

The cutting portions of the blades are serrated with castellations to assure a smooth even facial contact surface, even though the blades are thin, in that their combined laminated arrangements with their edges on a common plane prevents any one or more blades from digging into the surface of the skin; this is so because there are no sharp or ragged edges to contact the skin of a person. Nevertheless, every hair of the skin is positively and closely sheared as the razor of this invention is glided over the surface of the skin because of the plurality of cutting edges presented which are so positioned that they easily shear all the hairs while gliding smoothly and gently over the skin.

Certain of the blades of the razor are fixed and others are reciprocable, but all are, nevertheless,

2

relatively reciprocable in that the blades sandwiched between the fixed ones are rapidly vibrated. The movable blades are said to be rapidly vibrated, but they are in fact only moderately vibrated in comparison with other kinds and types of automatic razors, and this is due to the fact that applicant's blades are numerous and each blade provides a very large number of cutting edges.

10 One of the principal objects of this invention is to present a new and novel rapid shaver or shearer that is sturdy and simply built, has few parts, is self-contained in compact form, and is easy to make and economical to manufacture.

15 Another object is to present a slick gliding razor in which the cutting edges are but slightly in contact with the surface over which the razor glides, but cannot cut the skin, nevertheless, under light pressure, all hairs and the like in the path of the razor will cut close to the surface.

20 Another object is to provide a razor with a plurality of laminations of independent blades having a plurality of shearing battlements, the cutting edges of which do lightly contact the skin, but which, nevertheless, will not cut the skin at normal pressures while the blades closely and neatly cut all hairs in the razor's path.

25 Other objects, advantages and features of my invention will appear from the accompanying drawings, the subjoined detailed description, the preamble of these specifications and the appended claims.

30 Applicant is about to illustrate and describe one of the forms of his invention in order to teach one how to make and use the same, but it is to be understood that the drawings and description thereof are not to limit the invention in any sense whatsoever, except as positively limited by the appended claims.

35 In the drawings:

Fig. 1 is an enlarged top plan view of a razor with parts thereof being broken away,

Fig. 2 is a front elevational view of the razor shown in Fig. 1 with parts broken away,

40 Fig. 3 is a side elevational view of the entire razor device,

Fig. 4 is a side elevational view similar to the top portion of Fig. 3, but showing a slight modification thereof, and

45 Figs. 5, 6 and 7 are end elevational views of laminated blade portions of slightly modified forms of the invention.

50 The reference character 1 indicates the head portion of an electric rapid shaver or razor, and the numeral 2 indicates the body part which is

designed to be readily gripped by or held in a person's hand. The body portion 2 is a housing for an electric motor for operating the movable blades of the head, the motor being supplied with suitable electric current via of the two wire cord 3, and through the button type current control switch 4. A rotary shaft 5 extends from the armature of the motor and connects with a short shaft 6 which is slightly eccentric to shaft 5 through the medium of the short arm 7. Since it is desired to avoid all unnecessary friction and scraping action, the amount of the offset of the shafts 5 and 7 need only be about 0.006 inch in that the blades that are shifted by the shafts need only shift about 0.012 inch for the reason that the coarsest hair is no more than about 0.003 inch thick.

The top portion of the casing or housing 2, as shown, may be integral with the head 1 of the razor, and have the removable bottom cap or closure means 8 for gaining access to the motor chamber 9. Obviously, the motor would be a fractional horsepower one and be operated by the usual lighting or house alternating current of 60 cycle or 50 cycle.

Five flat cutting blades are shown numbered from 10 to 14 inclusive. Blades 10, 12 and 14 are fixed ones and do not move relatively to the housing, but do move relatively with respect to the movable blades 11 and 13. Therefore, the fixed blades have enlarged central holes 15 so as to make plenty of clearance for the shaft 6, but the movable blades have holes 16 which snugly receive the shaft 6 and are vibrated or reciprocated therewith. To allow the eccentric shaft 6 to revolve without affecting the straight line action of the movable blades, cutouts 16' are provided, note Fig. 1. The movable blades have cutouts 17 at the ends thereof to make plenty of clearance for the posts 18 and 19 which posts are shown as integral with the housing 2. The fixed blades, however, have holes 20 which snugly receive the posts. All the blades are superimposed one on the other, and held so by the curved plate-spring 21 which is held in position by the screws 22 and 23, these screws being threadedly engaged with the threaded bores 24 of the posts.

As said before, the cutting portions of the blades are serrated with castellation or castellated so as to distinguish their general configuration from angled shapes, as saw teeth, which produce sharp points, and which it is desired to avoid in this disclosure so as not to risk injuring the skin of a person. All the blades are castellated by providing their edges 25 and 26 with a plurality of evenly spaced apart cutouts 27, as shown, the edges 28 and 29 of each blade at the cutout portion thereof are ground sharp so as to present true right-angled keen edges 28' and 29'.

The razor shown in Fig. 4 is substantially the same as the one just explained except that a large number of flat thinner blades are employed which are numbered 30 to 36 inclusive. One of the razor edges is not shown squared but biased at a slight angle to present a slightly bevelled ground surface 37 so that the razor can be held against the skin at an angle and also for allowing the laminated shaver to attack the hairs in a slightly different manner than attacked by the ground and squared edge 38, note Fig. 3. The hairy skin of a person is indicated at 39 in Figs. 3 and 4, and is believed to be a fair representation as to how the hairs extend from the skin.

Figs. 5, 6 and 7 show only the laminated blade

ends in end elevation, as for instance, either the right or left extreme portion of the blades of Fig. 4, but these modified forms present different arrangements of contact edges for the skin; that is, in Fig. 5, the blades are so arranged that the combined edges of blades form a wide open V-shaped cross-sectional contour. This arrangement presents the two angled surfaces 40 and 41 and form an elongated ridge or edge 42 which extends the full length of the blade unit. The blades of this modification have been given the prime numbers of the reference characters designating the similar blades of Fig. 4 so as to more clearly indicate that the blade arrangement and the entire razor is the same except for the slight changes noted.

Fig. 6 shows the blade unit having formed at its gliding surface a curved or convexed surface 43, and the Fig. 7 shows a concaved surface 44. The various gliding surfaces shown in Figs. 4, 5, 6 and 7 all have their peculiar functions in receiving the hairs to be cut, the closeness of the cutting action, and the manner of exerting pressure upon the immediate surface of the skin as the razor glides along. It is now obvious that the gliding edges 37 and 38 need not necessarily be flat surfaces in order to satisfactorily and neatly shave the beard from a man's face or the hairs from any surface such as the skin of a person's arm, leg, neck, etc. Obviously, in view of this disclosure, the blades of the razor need not be flat ones as curved ones would work well and may possibly be preferred for some specific purposes.

It is, of course, understood that various changes and modifications may be made in the details of form, style, design and construction of the whole or any part of the specifically described embodiment of this invention without departing from the spirit thereof, such changes and modifications being restricted only by the limitations clearly expressed in the following claims.

Having thus described my invention, what is claimed as new and desired to be secured by Letters Patent is:

1. In a shearing device having a head and handle-like means to support it, a blade unit in the head having a plurality of laminations with one edge of each lamination adapted to be glided along a surface to be sheared, cutting edges extending from the said one edge inwardly of each lamination to present a large number of cutting edges along the length of the unit, alternate laminations having a fixed relation with the head and the other laminations having means for their reciprocation, said means to support the head having a motor with an eccentric pin extending from a shaft thereof which passes through all the blades, the reciprocable blades each having a perforation with perimetrical walls that engage the pin only on two opposed points thereof, and the fixed blades each having a perforation that is provided with walls that are well spaced from the pin.

2. In a razor device having a body portion, blade unit, and means for holding the unit onto the body portion, an eccentric pin projecting from the end of a motor shaft extending from the body portion, and through the blade unit, the unit comprising a plurality of side-by-side superimposed blades having holes therein to accommodate the pin, certain of the blades being movable relative to the other blades, said certain blades having portions of their holes snugly en-

gaging the said pin to follow the movement of said pin.

3. In a razor device having a body adapted to be held in a person's hand, a blade unit, and means for holding the blade unit to the body, the unit comprising a lamination of blades superimposed in side-by-side relationship and presenting a common gliding surface, each of the blades having one of its edges castellated and the edges of the castellations being sharp and extending to the gliding surface, and means extending from the body and attached to alternate blades for rapidly reciprocating them and presenting a plurality of cutting edges at the gliding surface of the device, said means extending from the body comprising an eccentric pin that revolves freely through an opening in the fixed blades, a hole through the end portions of the blades, said means for holding the blade unit to the body including a pair of spaced apart studs which pass through said last mentioned holes and which snugly engage and hold the fixed blades.

4. The device recited in claim 3 wherein the gliding surface is a flat surface and in a plane at right angles to the axis of the said means extending from the body.

5. The device recited in claim 3 wherein the gliding surface is a flat surface and in a plane at an acute angle to the axis of the said means extending from the body.

6. The device recited in claim 3 wherein the gliding surface has a plurality of small surfaces forming a plurality of planes with respect to the axis of the said means extending from the body.

7. In a shearing device, a body, a plurality of superimposed blades presenting a common gliding surface for contact with the surface to be sheared, alternate blades having fixed relation with a portion of the device and the other blades having means for rapidly reciprocating them, a plurality of cutting edges on each blade at an angle with respect to the gliding surface, and a resilient plate at one side of the blades having means for securing the blades in operative position with respect to the body.

8. In a shearing device having a head and handle-like means to support the head, a blade unit in the head having a plurality of fixed laminations and other laminations connected to a motor means in the handle-like means for reciprocating them snugly against the fixed ones, one edge of all the laminations having a common plane, and cutting edges extending from the common plane inwardly to present a large number of cutting edges along the length of the unit, an eccentric pin extending from a shaft of the motor which passes through all the blades, said other laminations being movable ones and having alined walls about an opening therethrough which engage the pin only along opposed sides thereof, and the fixed blades having alined walls about an opening which walls are permanently spaced from all surfaces of the pin.

9. In a razor device having a handle-shaped body, a blade unit, and means for holding the unit to the body, the unit comprising a lamination of blades superimposed in side-by-side relationship and presenting a common gliding surface, said body housing an electric motor having a shaft with an eccentric pin extending therefrom, a central opening through all the blades, alternate blades being fixed blades and having the walls of their openings in perfect alinement and spaced from the pin in all its positions, the other blades having the walls of its openings in alinement but with two of its opposed walls in contact with opposed points of the pin and its other walls spaced from the pin.
